ATTY.

UNITED STATES PATENT OFFICE.

JOHN HAACK, OF PORTLAND, OREGON.

ELECTRIC LANTERN.

1,384,017.

Specification of Letters Patent. Patented July 5, 1921.

Application filed May 10, 1920. Serial No. 380,223.

To all whom it may concern:

Be it known that I, JOHN HAACK, a citizen of the United States, residing at Portland, in the county of Multnomah and State 5 of Oregon, have invented a new and useful Improvement in Electric Lanterns, of which the following is a specification, reference being had to the accompanying drawings.

My invention relates to lanterns as a class. 10 The object of my invention is to provide an electric lantern, conveniently portable by hand, with an electric cell therein arranged to be easily accessible and a particular arrangement of electrodes and switches for 15 the cell and lamp. These objects, as well as other advantages, I attain by the construction, combination and arrangement of parts illustrated in the accompanying drawings which form a part hereof.

20 Figure 1 is a side elevation with parts in section, and lamp opened, indicated in dotted lines.

25 Fig. 2 is a top plan view of the body or cell container with cover removed, showing the cell.

Fig. 3 is a bottom plan view of the hinged top and cover showing contact parts.

Fig. 4 is a sectional view of the handle grip on line 4-4 in Fig. 1.

30 Like characters refer to like parts in the views.

The lantern has two members, the cell container being member 5, and the lamp and mechanism container, being member 6. 35 Within the member 5 is a recess of convenient size, in which an electric cell 7 of common type is placed, preferably of the character known as a dry cell. The cell has electrodes 8 on its upper surface, connected with its respective elements. A 40 carrying handle 9 is hinged on opposing sides to the member 5. The member 6 is hinged at the rear to the upper part of the member 5 by the hinge 10 and has a securing catch 11 in front. The member is formed with a hollow, horizontal grip or handle 12, having a reflector 13 secured upon its forward end and a socket 14 in its center adapted to receive a lamp 15. Electric 45 terminals 14^a and 14^b are placed in the socket and furnish the usual type of connection between the lamp and the circuit wires. Within the cap portion of the member 6, which fits over the top of the member 5, a disk, with circular insulations 16, 50 is rigidly secured. The disk has inner and

outer circular terminals 17. These terminals are positioned to engage the respective cell electrodes 8, immediately beneath them, when the lantern is closed. An insulated 60 wire 18 extends from the inner terminal 17 to an insulated conducting terminal upon and near the rear end of a bar 19, which is secured in the handle 12. A spring closer arm 20 has one end integral with the said 65 rear bar terminal, its free end extending below a second insulated conducting terminal upon and near the forward end of the bar 19 in a position wherefrom the free end of the arm 20 may be pressed into engagement with the opposing terminal above. A wire 18' extends from the outer terminal 17 to the socket terminal 14^a. With a lamp in place as shown, the circuit continues through the lamp to the opposing terminal 75 14^b, thence by a connecting wire to the forward terminal on the bar 19. The closer arm 20 is retained by tension free of the opposing terminal. A finger block 21 is slidably arranged within the handle 12 longitudinally below the arm 20. The block 21 has a finger projection 22 extending downwardly through a slot in the handle 12 and the upper, forward part of the block has an inclined surface which engages the arm 20. 80 85

It will be seen that when the lantern is closed with the cell placed in the member 5, its electrodes are at all times in engagement with the circular terminal strips 17, regardless of how the cell may be turned. It 90 will be seen also that a direct and continuous metallic circuit is provided through the circuit closer and lamp. The common practice is to carry a circuit through a ground in the lamp but this dissipates the electric 95 energy, requires more power and weakens or exhausts the cell much sooner. This difficulty I have overcome and find the lamp in my device can be kept lighted with the same cell for a much longer time and with 100 a better illumination. The finger block 21, when moved forwardly, engages the arm 20, raising it upon the horizontal surface of the block and the contact point at the end engages the forward terminal on the bar 19, 105 the block being retained in this position by the downward pressure on it of the arm 20. The circuit is thus closed and the lamp kept lighted. Upon pressing the block rearwardly the circuit is opened and the light 110 extinguished. It will also be noted that the block may be pressed upwardly when the

circuit is opened. This enables a momentary closing and opening of the circuit to be made for flashlight purposes. The hinging of the two members in the manner shown 5 provides an arrangement whereby the lantern may be easily opened to insert or remove a cell and the mechanical parts in the upper member easily inspected or repaired.

I claim—

- 10 1. In an electric lantern a hinged cover, having in combination therein, an incandescent lamp, a rigidly secured, downwardly facing disk, having two circular insulated terminals therein, one of which is connected 15 with one terminal of the lamp, and a circuit bar having one terminal connected with the opposing terminal of the lamp, its other terminal connected with the opposing terminal of the aforesaid disk, also a closing arm extending from the last mentioned bar terminal downwardly, and a movable finger block, arranged in a manner to allow it to slide below the arm and press its free end into contact with the opposing bar terminal 20 and thus retain it, also to allow the block to be lifted vertically to cause its free end to engage the opposing bar terminal while held in such position.
- 25 2. In an electric lantern, the combination 30 of, upper and lower casing members hinged together, an electrical cell, having two electrodes on its upper end, positioned in the lower member, an incandescent lamp in the upper member, a circuit bar in the upper

member, having a downwardly extending 35 closing arm with a free end, a slideable and vertically movable finger block, formed and arranged in a manner to allow it to slide below, press the arm upon the bar and thus retain it, also to allow the block to be lifted 40 vertically and thereby cause the arm to engage the bar while held, and an all metallic direct circuit between the lamp and cell and through the closing means.

3. In an electric lantern, the combination 45 of, upper and lower casing members hinged together, an electrical cell, having two electrodes on its upper end, positioned in the lower member, an incandescent lamp in the upper member, a disk secured in the upper 50 member, having two circular insulated terminals in position to engage the opposing cell electrodes in whatever position placed, when the members are closed, a circuit bar in the upper member, having a downwardly 55 extending closing arm, a movable finger block, arranged in a manner to allow it to slide below, press the arm upon the bar and thus retain it, also to allow the block to be lifted vertically and thereby cause the arm 60 to engage the bar while held, and an all metallic direct circuit between the lamp and through the closing means.

JOHN HAACK.
